UNITED STATES PATENT OFFICE.

ALWILL URBAHN, OF PATERSON, NEW JERSEY, ASSIGNOR TO JACOB MAY,
OF BROOKLYN, NEW YORK.

MACHINE FOR BENDING METAL.

SPECIFICATION forming part of Letters Patent No. 313,459, dated March 3, 1885.

Application filed June 10, 1884. (No model.)

To all whom it may concern:

Be it known that I, ALWILL URBAHN, a resident of Paterson, in the county of Passaic and State of New Jersey, have invented an 5 Improved Machine for Bending Metal, of which the following is a full, clear, and exact description, reference being made to the accompanying drawings, in which—

Figure 1 is a plan or top view of my improved 10 machine for bending metal. Fig. 2 is a longitudinal vertical section of the same, taken on the plane of the line *c c*, Fig. 1. Fig. 3 is a vertical cross-section of the same, taken on the plane of the line *h h*, Fig. 1, and showing the 15 clamping-jaw open. Fig. 4 is a similar section showing the clamping-jaw closed. Fig. 5 is an edge view of the metal to be bent; Fig. 6, a face view of the same, and Fig. 7 an edge view of said metal after it has been bent.

20 The object of this invention is to produce a machine for bending straps of metal such as that used in grated doors or windows; and the invention consists in combining with the frame or main block of the machine a trans- 25 verse lever-jaw for holding the metal to be bent and a separate bending-lever carrying an attachment or projection for engaging the metal to be bent and crowding it against another attachment or projection which is carried by the above-mentioned frame or block.

30 In the drawings, the letter *A* represents a block of metal or other substance, of suitable size and form, which block is adapted to be clamped by a vise to a bench, or may be a rigid projection on a table or frame; hence 35 this block constitutes, in fact, the supporting frame of the machine. The upper face of this block *A* is level, excepting where the same carries a projecting piece, *B*, which serves as 40 an abutment for leaning the metal to be bent against, and also furnishes the edge *a*, which determines the angle to which the metal is to be bent.

To the lower part of the block *A* is piv- 45 oted, by the horizontal pin *b*, a lever, *C*, which carries an L-shaped jaw or head, *d*, that extends over the upper face of the block *A*, as is indicated in Figs. 3 and 4. To the end of the block *A* is also pivoted, by a vertical pivot, 50 *e*, a lever, *D*, the upper face of which is substantially on a level with the upper face of

the block *A*, but which carries on its top a projection, *f*, or bending-lug.

The piece of metal to be bent, which is shown at *E* in Figs. 5 and 6 and indicated by dotted lines in Fig. 1, is placed upon the block *A* and lever *D*, so as to be in contact substantially on one side with the projection *B* of the block *A* and on the other side with the projection *f* of the lever *D*. This appears 60 clearly from the strap *E*, which is shown by dotted lines in Fig. 1, and more particularly from the straight wing or end piece, *g*, of said strap *E*, which is shown in said figure. This being the arrangement and disposition of the 65 parts, the attendant now depresses the lever *C* so as to move it from the position which is shown in Fig. 3 to the position which is shown in Fig. 4, thereby clamping the strap *E*, of metal, and holding it tight between the head 70 *d* of the lever *C* and the projection *B* of the block *A*. The attendant next turns the lever *D* on its pivot *e*—that is to say, from the position which is shown by full lines in Fig. 1 into about the position which is shown by 75 dotted lines in that figure. By this motion the projection *f* of the lever *D* carries the wing or end portion, *g*, of the strap *E* against the obliquely-set face *a* of the projection *B*, whereupon the end portion, *g*, will assume the 80 position indicated for it at *h* in Fig. 1.

I am not confined to the use of an oblique-edged projection, *B*, on the block *A*, as the face *a* may be rounded or otherwise formed to produce the requisite angle or bend in the 85 strap *E*. In fact, the projection *B* is secured by bolts *i* to the block *A*, and can be removed to allow another projection with a differently-formed face to be put in its place, and in like manner the projection *f* of the lever *D* is fastened by bolts *j* to the lever *D*, and can therefore be removed and replaced by another of 90 different length, thickness, or form.

If the metal *E* to be bent is perforated before bending, as shown in Fig. 6, and if it is 95 desired to gage the angle with reference to its distance from one or the other of such perforations, it is desirable to have a gage-pin, *l*, inserted in the projection *B*, as shown in Fig. 3, a spring, *m*, being placed behind said pin 100 to push it out of the projection *B*, as appears clearly from Fig. 3. The pin may then be

put through the perforation of the strap E before the latter is bent; and yet, if an unperforated strap E should have to be bent, the pin will be crowded against the spring m into 5 the socket provided for its reception in the projection B, and will not be in the way of such unperforated strap.

I claim—

1. The combination of the block A, having 10 rigid projection B and bending-face a, with the clamping-lever C, which is pivoted to the block A and carries the head d, and with the

bending-lever D, which is also pivoted to the block A, and provided with the rigid projection f, substantially as herein shown and de- 15 scribed.

2. The combination of the block A, having rigid projection B, with the spring m, pin l, lever C, and lever D, the lever D having the projection f, substantially as described.

ALWILL URBAHN.
